UNITED STATES PATENT OFFICE

ERNEST M. WHITE, OF GLOBE, ARIZONA.

ENGINE-OILING SYSTEM.

1,101,366.

Specification of Letters Patent. Patented June 23, 1914.

Application filed November 21, 1911. Serial No. 661,532.

To all whom it may concern:

Be it known that I, ERNEST M. WHITE, a citizen of the United States, residing in Globe, Gila county, Arizona, have invented 5 certain Improvements in Engine-Oiling Systems, of which the following is a specification.

One object of my invention is to provide a novel arrangement and construction of 10 containers and conductors especially adapted for use in the crank case of an internal combustion or other form of engine, whereby the longitudinal inclination of the apparatus in either direction shall automatically 15 cause an increased body of lubricant to be collected and put in active circulation at the points where it is supplied to the cranks of the engine; the idea being to render larger bodies of lubricant available at 20 such times as the engine is doing more than its normal amount of work and incidentally is longitudinally inclined in either or both of two directions.

Another object of the invention is to provide 25 a novel form of lubricant container for use in connection with the crank of an engine, whereby a greater quantity of lubricant is automatically supplied to the crank whenever the engine and therefore the crank 30 case and attached parts are tilted in either of two directions beyond a predetermined amount. There is thus secured an ample supply of lubricant regardless of whether the front of said engine be elevated or depressed.

These objects and other advantageous ends I secure as hereinafter set forth, reference being had to the accompanying drawings, in which:—

40 Figure 1, is a longitudinal vertical section of the crank case of an engine, illustrating my invention as applied thereto; Fig. 2, is a transverse vertical section of the crank case taken on the line a—a, Fig. 1, and Figs. 3 and 4, are fragmentary transverse vertical sections illustrating modified forms of the auxiliary oil container.

45 In the above drawings 1 represents a casting constituting the lower portion of a crank case in the present instance designed for use in connection with a four cylinder engine. The crank shaft of this engine is illustrated at 2 and it has connected to certain of its cranks 3, 4 and 5 the connecting rods 6, 7 and 8. Each of the connecting rods

is provided with a downwardly extending projection 9 designed to periodically enter an auxiliary oil reservoir hereafter described for the purpose of collecting and delivering to the parts to which it is attached 60 the lubricant necessary to maintain it in proper operative condition. With this idea in view, there is provided under each crank a basin-like container 10; it being noted that in the case illustrated all of said containers are integral parts of a single casting, although in some cases they may be made as 65 separate units without departing from my invention. Below these containers the crank case is continued downwardly to form a 70 main oil reservoir 11 which extends underneath all of the auxiliary containers 10 and has connected to its lower portion the intake of a pump 12 operated from any suitable part of the engine. The outlet conduit 13 of 75 the pump is connected to a conduit 14 extending longitudinally of the crank case and having an outlet indicated in dotted lines at 15 opening into each of the auxiliary containers 10. These latter each have a central 80 transversely extending depression or cavity 16 designed to receive the projection 9 of the connecting rod to be supplied with lubricant from that particular container, and as shown, the bottoms of each container 10 are 85 inclined downwardly toward its transverse cavity. Each of these latter has an outlet 17 communicating with a passage 18 constituting a level maintaining trap which passes under it and has an outlet 19 on the 90 side thereof opposite that into which the outlet 17 opens. Adjacent said outlet 17 the passage 18 has an opening or passage 20 extending upwardly through the bottom of its auxiliary container, so that there is free 95 admission of air to this end of the passage independently of the outlet 17 of the cavity 16.

Under operating conditions, the main reservoir 11 is filled with oil, preferably to 100 the level shown and the operation of the pump 12 causes this oil to be delivered to the various auxiliary containers or reservoirs 10, which are filled thereby to a level ordinarily determined by the height of the 105 outlet opening 19 of the passage 18. As shown in Fig. 1, the arrangement is such that under these conditions there is a body of oil in each cavity 16 and also in each passage 18, so that as the connecting rods 6 110

alternately enter and leave the lower part of the crank case, their projections 9 scoop up or otherwise distribute a certain amount of lubricant from the depressions 16 in the desired manner. If now the engine to which the crank case is attached be tilted so that the center line of the crank shaft occupies the position indicated in dotted lines at $x-x$, then it is obvious that while the outlets 19 are all lowered, the depressions 16 each collect a body of oil greater than that normally in them, since each outlet 17 is raised. As a result the various projections 9 enter larger bodies of oil so that correspondingly increased amounts thereof are delivered by said projections to the parts requiring lubrication. As soon as the engine is returned to its level or normal position and consequently operates under normal conditions, the surplus liquid within the cavities 16 immediately passes through the outlet 17 and channel 18, overflowing at 19 into the main reservoir. On the other hand, if the crank case were so inclined that the line of the crank shaft occupied the position indicated by the line $y-y$, there would again be provided an increased depth of oil in the depressions or cavities 16, for while the outlet 17 would be lowered, the final outlets 19 would be raised. The auxiliary reservoirs thus retain the desired larger body of lubricant which is delivered by the projections 9, in the ordinary manner, to the parts requiring lubrication. As before, the return of the engine to its normal level at once permits the surplus lubricant in the auxiliary containers to be discharged into the main container 11 on account of the lowering of the outlets 19, and it is noted that the siphoning-out of lubricant from the auxiliary containers is prevented by the air passages 20 which open into the passages 18.

By means of the construction above described increased amounts of lubricant are automatically supplied to the engine whenever the latter is longitudinally inclined in either direction and this is particularly advantageous since, especially in marine work, such inclination would ordinarily result in or be consequent upon such an action of the engine as would require increased lubrication.

In some instances the auxiliary containers may be given the form shown in Fig 3, having their depressions 16^a made with concave instead of perpendicular walls and cut away at one side so that the outlet 17 and the air passage 20 are replaced by a single large opening performing the same functions.

Another form of auxiliary container is shown in Fig. 4, in which the cavity 16 is substantially the same in form as those shown in Figs. 1 and 2, although as in the case shown in Fig. 3, the air passage 20 and outlet 17 from the depression are replaced

by a vertically extending slot or recess, whose lowest portion constitutes the level-determining edge of the depression 16.

I claim:

1. The combination of an oil container 70 formed to receive a moving part of an engine with a discharge conduit, in the form of a trap, connected thereto and having both its inlet and its outlet at substantially the normal oil level of said container.

2. The combination of an oil container for an engine, the same having an oil containing cavity formed to receive a moving part of the engine; a level maintaining trap connected to said container to receive oil discharged therefrom, the inlet and outlet of said trap being substantially at the normal level of oil in the container; and means for supplying oil to said container.

3. As a new article of manufacture, a 85 lubricant container formed to receive a moving part of an engine; the same having a lubricant containing cavity provided with an outlet on one side, with a conduit connected to said outlet and having its discharge on that side of said container opposite said outlet.

4. As a new article of manufacture, a lubricant container formed to receive a moving part of an engine; the same having a 95 lubricant containing cavity, and provided with an outlet passage connected to the cavity, said passage opening out of one side of the container and discharging on the opposite side thereof at substantially the same 100 normal level.

5. As a new article of manufacture, a lubricant container formed to receive a moving part of an engine; the same having a lubricant containing cavity, and provided 105 with an outlet passage connected to the cavity, said passage opening out of one side of the container and passing under the same to a discharge opening on the opposite side thereof.

6. As a new article of manufacture, a lubricant container for an engine, having a lubricant holding cavity and provided with an outlet passage; said passage opening out of one side of the container and discharging 115 at the opposite side thereof at substantially the same level; there being an air vent to said passage placed to prevent siphoning of the liquid therefrom.

7. The combination in lubricating apparatus of a main container; an auxiliary container discharging into said main container means for causing the liquid holding capacity of said auxiliary container to be increased when it is tilted in either of two 120 opposite directions from a predetermined position; with means for supplying lubricant to the auxiliary container from the main container.

8. The combination in lubricating appa- 130

ratus of a main container; a plurality of auxiliary containers mounted therein discharging into said main container; means for causing the liquid holding capacity of 5 each auxiliary container to be increased when the main container is tilted in either of two opposite directions from a predetermined position; with means for delivering lubricant from the main container to the 10 auxiliary containers.

9. The combination in lubricating apparatus of a main container; apparatus to be supplied with oil provided with a plurality of oil receiving parts; a plurality of auxiliary containers each formed to intermittently receive one of the oil receiving parts under operating conditions and each having an outlet conduit opening out of one of its sides and discharging into the main container 15 on its opposite side at substantially the same level; with means for delivering oil from the main container to the auxiliary containers.

10. The combination of a plurality of 25 moving parts, each having an oil receiving member; a main oil container; a plurality of auxiliary containers, each having its lower portions formed to constitute an elongated cavity for the intermittent reception of an 30 oil receiving member; there being a conduit connecting with one side of each of said cavities and passing under the same to a discharge at the opposite side thereof; with means for delivering oil from the main container 35 to the auxiliary containers.

11. The combination of an engine crank case having a main oil container; a plurality of independent auxiliary oil containers; moving members mounted to periodically 40 splash up oil from said latter containers; and means for supplying oil from the main container to each of the auxiliary oil containers, said latter containers each having a level maintaining trap arranged with 45 its inlet and outlet at substantially the normal oil level of the auxiliary containers.

12. The combination of a crank case; a

lubricant container therein placed to be periodically entered by the crank of an engine and having an outlet on one side; with a 50 conduit connected to said outlet and discharging on that side of the container opposite the outlet, the inlet and discharge ends of said conduit being below the upper edges of said container.

13. A splash trough for an engine provided with an overflow outlet; with a conduit connected to said outlet and passing under said trough, the discharge end of the conduit being on the side of the trough opposite that having the overflow outlet, and the ends of said conduit being below the upper edges of said trough.

14. The combination of a main container; a plurality of auxiliary containers mounted 65 therein in positions to be respectively entered by moving parts of an engine, each of said containers having an outlet; conduits respectively connected to said outlets, the inlet and outlet ends of each of the conduits being on opposite sides of its auxiliary container and below the upper edges thereof; with means for transferring oil from the main container to the auxiliary containers.

15. The combination of a crank case forming a main lubricant container; an auxiliary container mounted therein in position to be periodically entered by the crank of an engine and having an overflow outlet; a conduit connected to said outlet, passing under 80 said auxiliary container and turning upward at the side thereof opposite that having the overflow, the ends of said conduit terminating below the upper edges of said auxiliary container; and means for transferring oil from the main container to the auxiliary container.

In testimony whereof, I have signed my name to this specification, in the presence of two subscribing witnesses.

ERNEST M. WHITE.
